(21) Appl. No.: **29/335,759**

(57) **CLAIM**

(22) Filed: **Apr. 21, 2009**

The ornamental design for a thermal insulation sleeve for a tea pot, as shown and described.

(30) **Foreign Application Priority Data**

Oct. 27, 2008 (WO) DM/070893

DESCRIPTION

(51) **LOC (9) Cl.** **07-01**

FIG. 1 is a perspective view of the thermal insulation sleeve for a tea pot;

(52) **U.S. Cl.** **D7/607; D7/387; D7/624.2**

FIG. 2 is a first side elevation view thereof;

(58) **Field of Classification Search** D7/619.1,

FIG. 3 is a second side elevation view thereof;

D7/624.2, 607, 300, 387; D6/610; 62/457.1–457.9;
220/737, 739, 902, 903

FIG. 4 is a third side elevation view thereof;

See application file for complete search history.

FIG. 5 is a fourth side elevation view thereof;

(56) **References Cited**

FIG. 6 is a top view thereof;
